[57] CLAIM

The ornamental design for an eyeglass holder, as shown and described.

DESCRIPTION

FIG. 1 is a perspective view of an eyeglass holder showing my new design, the broken lines showing an eyeglass being for illustrative purposes only and forming no part of the claimed design;

FIG. 2 is a front elevational view thereof, the rear being a mirror image;

FIG. 3 is a right side elevational view thereof;

FIG. 4 is a left side elevational view thereof;

FIG. 5 is a top plan view thereof; and,

FIG. 6 is a bottom plan view thereof.
